UNITED STATES PATENT OFFICE.

JOHN CONRAD, OF BURLINGTON, IOWA.

GATE ROLLER AND HINGE.

SPECIFICATION forming part of Letters Patent No. 233,476, dated October 19, 1880.

Application filed August 16, 1880. (No model.)

To all whom it may concern:

Be it known that I, JOHN CONRAD, of Burlington, Iowa, have invented a new and useful Gate Roller and Hinge, of which the following is a specification.

Figure 1 represents a side elevation of a device embodying the present invention. Fig. 2 represents an end view of same. Fig. 3 represents a vertical central section of device shown in Fig. 1.

Similar letters of reference indicate similar parts.

My invention is intended to secure a strong durable gate-roller which will turn freely to either side and will at the same time be firm and steady. I accomplish this by means of the devices hereinafter set forth and described.

In the drawings, A is a wrought-iron guide-frame in a single piece, bent at the bottom so that the sides will form the parallel uprights a a', which are journaled to secure the axle of a cast-iron roller, B.

The frame A rests upon a projecting arm, D, screwed horizontally into an upright post.

The flat bottom of the frame A is perforated at b to receive and permit the passage of the tap-

bolt C, which also passes through the end of the arm D, and is then screwed into the threaded perforation d in the band of a double flange, E, made in one piece, which serves as an immovable nut, and at the same time fits closely down over the edge of a board to steady and hold firm the entire device, the board being directly beneath the projecting arm D. Thus, when the hinge and roller are fixed to the gate-post by screw D, the gate can have a free horizontal swinging movement on the tap-bolt C, while it will have free sliding movement on the roller B, upon which one of its bars will rest.

What I claim, and desire to secure by Letters Patent, is—

The frame A, having roller B journaled therein, combined with screw-threaded arm D and flange E by the tap-bolt C, which acts as a hinge on which the parts can be moved, substantially as and for the purpose set forth.

JOHN CONRAD.
